(57) **CLAIM**

The ornamental design for a wire terminal, as shown and described.

DESCRIPTION

FIG. 1 is a top, front and right side perspective view of a wire terminal showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is a bottom, front and left side perspective view thereof.

The broken line in the FIG. 2 represents unclaimed environment only and forms no part of the claimed design.
